[57] **CLAIM**

The ornamental design of a dual action sander, as shown and described.

DESCRIPTION

FIG. 1 is a top plan view of a dual action sander according to the present invention;

FIG. 2 is a left side elevation view of a dual action sander according to the present invention;

FIG. 3 is a right side elevation view of a dual action sander according to the present invention;

FIG. 4 is a bottom view of a dual action sander according to the present invention;

FIG. 5 is a front elevation view of a dual action sander according to the present invention; and,

FIG. 6 is a rear elevation view of a dual action sander according to the present invention.

The structural features depicted by means of broken lines in the drawing figures have been shown for illustrative purposes only and form no part of the claimed design.
